UNITED STATES PATENT OFFICE.

FREDERICK R. BISHOP, OF NORTH ATTLEBORO, MASSACHUSETTS, ASSIGNOR TO THE BISHOP COMPANY, INC., OF NORTH ATTLEBORO, MASSACHUSETTS.

EYEGLASS-HOLDER.

1,270,106.

Specification of Letters Patent. Patented June 18, 1918.

Application filed February 9, 1918. Serial No. 216,344.

To all whom it may concern:

Be it known that I, FREDERICK R. BISHOP, a citizen of the United States, residing at North Attleboro, in the county of Bristol 5 and State of Massachusetts, have invented certain new and useful Improvements in Eyeglass-Holders; and I do declare the following to be a full, clear, and exact description of the invention, such as will enable 10 others skilled in the art to which it appertains to make and use the same.

My invention relates to improvements in eye glass holders of the type employing a casing to be pinned or otherwise secured 15 on the wearing apparel, a spring-wound reel in said casing, and a cord or chain wound on said reel and adapted for attachment to the eye glasses; and the principal object is to provide a novel construction and arrangement of parts for normally preventing the 20 spring of the reel from winding the latter, the construction of such means being so simplified as to cheapen manufacture without lack of efficiency.

With the foregoing general object in view the invention resides in the novel features of construction and unique arrangements of parts to be hereinafter fully described and claimed, the descriptive matter being supplemented by the accompanying drawing 30 which forms a part of this specification and in which:

Figure 1 is a rear elevation;

Fig. 2 is a sectional view on the plane of 35 the line 2—2 of Fig. 1;

Fig. 3 is an edge view;

Figs. 4 and 5 are sectional views on the planes of the lines 4—4 and 5—5 respectively of Fig. 2; and

Fig. 6 is a perspective view of the cord reel.

In the drawings above briefly described, the numeral 1 designates any preferred type 45 of flat circular casing having the usual or any preferred form of pin 2 or other attaching device on its rear side, the edge of said casing having an opening 3 through which the eye glass cord or chain 4 passes from the reel 5 which is located within the casing. 50 The reel 5 is formed of stamped metal and its ends are provided with circular recesses 6 and 7, the former receiving the winding spring 8 while a pawl 9 is located in the recess 7 to normally prevent winding movement of the reel. The reel is rotatably 55

mounted on a fixed central post or shaft 10 having one end reduced, passed through the rear side of the casing 1, and upset at 11. The post 10 has its opposite sides milled or otherwise flattened at 12 adjacent its anchored end, said flattened sides being located in the recess 7 for coöperation with the pawl 9, and the end of the post opposite said anchored end is free of connection with the casing and is provided with a longitudinal 60 slit in which the spring 8 is anchored.

The pawl above referred to is stamped from a single piece of sheet metal of proper thickness and said pawl is formed in substantially the shape of a J, one end of said 70 pawl having a V-shaped notch 13 while the other end thereof is increased in width to form a weight 14. A lug 15 is stamped inwardly from the sheet metal wall of the recess 7 and is received loosely in the notch 75 13 to pivotally mount the pawl so that the latter may so swing as to either engage or disengage the flattened sides 12 of the shaft 10, the inner curved edge of the pawl being provided with an integral lug 16 coöoperating 80 with said flat sides as shown in Fig. 4. Normally, that is when the cord 4 is unwound from the reel, the lug 16 engages one flat side 85 12 of the shaft 10 as shown in Fig. 4 so that rewinding of the reel is prevented. In order to release the pawl however it is simply necessary to give a rather sharp pull on the cord and to then quickly release the same, but the moment the movement of the reel is sufficiently slow to permit the weight 14 to drop 90 against centrifugal force, the lug 16 will again engage the shaft 10 to arrest further movement of the reel.

The exact construction and mounting of the pawl 9 and of the post 10 is extremely 95 simple and inexpensive and is therefore easy to manufacture, yet these features do not result in any loss of efficiency or durability. It is this novel arrangement of parts that 100 forms the gist of the present invention and upon which Letters Patent is sought.

I claim:

1. In an eye glass holder, the combination of a flat casing, a fixed central shaft in said casing having its opposite sides flattened at 105 one end, and a spring-wound stamped metal cord reel in said casing mounted rotatably on said shaft, one end of said reel having stamped therein a circular recess at whose center the flattened end of said shaft is lo- 110

cated; together with a lug stamped from the wall of said recess and extending into the latter, and a J-shaped pawl in said recess having in one end a notch into which said lug projects to pivotally mount said pawl, the other end of said pawl being weighted and the inner curved edge of said pawl having a projecting lug to engage the flattened sides of said shaft to normally prevent winding movement of the reel.

2. A structure as specified in claim 1, said shaft being anchored at one end to the casing and being free of connection with said

casing at its other end, the flattened sides of said shaft being located adjacent the anchored end thereof and the free end of said post having a longitudinal slit in which the reel winding spring is anchored. 15

In testimony whereof I have hereunto set my hand in the presence of two subscribing witnesses:

FREDERICK R. BISHOP.

Witnesses:

ARTHUR O. BISHOP,

EVA C. TUFTS.
